SHOEMAKING METHOD

Fred Maccarone, Brooklyn, N. Y., assignor to Del-Mac Shoe Process Corporation, New York, N. Y.

Original application May 15, 1933, Serial No. 671,109. Divided and this application October 23, 1934, Serial No. 749,526. In Canada April 25, 1934

11 Claims. (Cl. 12—146)

My present invention relates to shoe making and is a division of matter disclosed in my co-pending application Serial No. 671,109 filed May 15, 1933.

5 A principal object of my invention is to provide an improved and more economical method of producing an outsole and a complementary insole therefor, whereby the insole and outsole portions of the shoe are patterned and sized at the same time from a single piece of sole material to insure that the insole and outsole portions are of relatively proper shapes and sizes.

10 A further object is to provide an improved and simplified method of making shoes of the type originally taught in my United States Patent No. 1,569,823, wherein an insole, to which the upper is affixed, includes an integral heel portion, a shank portion and a ball portion having a central opening therein defining a continuous marginal rand 15 extending from the front of one side of the shank around the toe and to the front of the opposite side of the shank to afford means for initially affixing the upper to the insole, and an outsole is provided having a marginal depression conforming to the rand for receiving the same with the upper attached thereto, whereby the central portion of the inner face of the outsole is disposed flush with the upper surface of the rand.

20 Referring to the drawings:

25 Figure 1 is a plan view of a combination pattern or template and cutting die for rounding an outsole and initially forming an insole for use therewith.

30 Figure 2 is a cross sectional view on a larger scale of the pattern shown in Figure 1, having a piece of sole material clamped thereagainst and illustrates the sole rounding operation as well as the initial insole forming operation.

35 Figure 3 is a fragmental view similar to Figure 2, illustrating a modification of the combination pattern and die.

40 Figure 4 is a plan view of the rounded sole showing incisions therein cut by the pattern blades defining an insole.

45 Figure 5 is an enlarged section taken on line 5—5 of Figure 4.

50 Figure 6 is a plan view of the female portion of a die employed to centrally depress the ball portion of the rounded and incised sole which is shown lying thereon.

55 Figure 7 is a cross sectional view taken on line 7—7 of Figure 6 and illustrates, on a larger scale, the ball portion of the sole depressed between the male and female die portions.

Figure 8 is a longitudinal sectional view illus-

trating the method by which the rounded and incised sole is split to provide the complementary and properly sized outsole and insole portions.

Figure 9 is a longitudinal section thru the insole portion.

Figure 10 is a longitudinal section thru the outsole portion.

Figure 11 is a longitudinal section thru the backing piece employed to support and reinforce the sole during the splitting operation illustrated in Figure 8.

Figure 12 is an inverted plan view of the insole with the upper lasted and secured thereto.

Figure 13 is a longitudinal section taken thru the insole and portions of the attached upper.

Figure 14 is a longitudinal section illustrating the ball tread portion of the shoe with the outsole assembled thereto, and

Figure 15 is a side elevation of a completed shoe, shown partly in section to reveal the finished relationship of the sole portions.

In carrying out my present invention I prefer to first incise the sole material to define an insole portion of suitable size, thickness and proportions, and then to round the outsole from the same piece of material in relation to the insole thus defined.

To accomplish this I may employ a pattern or template, as shown in Figure 1, which comprises a body portion 20 and side and end portions 21 and 21, between which I removably secure thin and flexible cutting blades 22—22 by means of countersunk screws 23—23 etc. The blades 22 are positioned and arranged to extend outwardly from the face of the pattern a distance corresponding to the thickness of the insole to be provided and are contoured in conformity with the sole portion of the last on which the shoe is to be assembled.

As indicated in the drawings, it is usually not necessary that the full outline of the insole be incised in the sole material or that the blades 22 extend to accomplish that purpose inasmuch as the insole ordinarily conforms in size and shape to the outsole over the shank and forward portions of the heel and may be formed with the outsole in the sole rounding operation hereafter to be described.

In all other respects the pattern is of the usual type heretofore employed and is provided with holes therethru at 24 and 24 to receive the positioning pins 25—25 of a conventional sole rounding machine, fragmental supporting parts of which are indicated at 26 in Figures 2 and 3.

When the pattern has been positioned on the

sole rounding machine, a piece of sole material 27, of uniform thickness, is laid over the pattern and rests upon the cutting edges of the blades 22, whereupon the clamp 28 of the rounding machine 5 is forced down upon the material, causing the blades 22 to cut into the material and firmly holding the material against the face of the pattern during the rounding operation performed by the knife 29, as indicated in Figures 1 and 2. The 10 rounded sole 30 is then taken from the machine and appears with incisions therein as indicated at 32—32 in Figures 4 and 5.

As illustrated in Figure 3, the blades 22 may be made to extend from both faces of the pattern 15 so that alternate faces thereof may be employed to form the sole portions of a mated pair of shoes.

Although I have found the foregoing method of producing the rounded and incised sole 30 20 economical and otherwise of advantage, it will be understood that the sole as it appears in Figures 4 and 5 may be provided in other ways than that above described for the purposes of carrying out the further operations of my im- 25 proved method, and that the sole may first be rounded and subsequently incised to define the insole portion if desired.

From the description thus far, it will be apparent that if the sole 30 were now to be split 30 within the depth of the incisions 32, the resulting divisions will comprise two sole portions of different sizes and proportions suitable for use as insole and outsole portions, respectively, of a shoe, and that waste marginal portions corre- 35 sponding to the material lying outside of the incisions and within the depth thereof will also result.

Before performing such splitting operation, however, I prefer to inflex or depress the central ball tread portion of the rounded and incised sole 30 a distance somewhat greater than the depth of the incisions 32. This I accomplish by pressing the sole between the male and female elements, 33 and 34 respectively, of a swage or 45 pressing die, as illustrated in Figure 7.

After removal from the pressing die, the sole is reenforced by a perforate backing strip 36 (see Figure 11), which is formed to complement the depressed portion of the sole and is preferably 50 made of a durable and somewhat flexible composition material. The sole thus backed up, is then passed between the rollers 37—37 of a conventional leather splitting machine, the splitting blade 38 of which is positioned to cut within 55 the depth of the incisions 32 and above the bottom of the depressed area 35, so that when the sole has been split its full length, an insole portion 39, perforate centrally of its ball tread portion, and an outsole portion 40, is provided. 60 Waste marginal portions 41 also result from this operation, as will be readily understood.

The insole 39, formed as above, comprises an integral heel portion, a shank portion and a ball portion, the said ball portion having a central 65 opening therein defining a continuous marginal rand 39' extending from the front of one side of the shank around the toe and to the front of the opposite side of the shank.

The insole 39 is next lasted to the upper 42 of 70 the shoe to which it is secured by any of such special adhesives as are well-known in this art, or by other suitable means, preliminary to which a patch 43 may be removably pasted to cover the perforate portion of the insole.

75 The outsole 40 is then placed in position over

the lasted insole and the depressed portion 35 thereof is forced back into its original normal condition, as illustrated in Figure 14. In this manner a marginal depression 40' is defined on the inner side of the outsole which conforms to the rand 39' and receives the same with the upper attached thereto, whereby the central portion 35 of the inner face of the outsole is disposed flush with the upper surface of the rand. 5

The remaining steps necessary to complete the 10 shoe are the usual ones consisting in removing the patch 43, assembling the sole lining 50 and affixing a heel 51.

Many modifications in the method and means here taught will become apparent from this disclosure to those skilled in the art to which this invention relates and I desire, therefore, to have the foregoing considered merely illustrative of my invention as defined in the here appended claims: 15

1. In shoe making, the method of forming an 20 outsole and a complementary insole from a single piece of material by incising the material with cuts defining margins of an insole, said cuts extending to a depth corresponding to the thickness 25 of the insole desired, rounding an outsole from said material in relation to the insole thus defined, then depressing the sole over a central area of the ball portion thereof, then splitting the sole above the depressed area and within the 30 depth of said cuts to obtain an insole therefrom, and then restoring the sole to its normal undepressed condition; the sole thus provided having a ball portion centrally elevated in thickness and the insole thus formed having an opening in the ball portion thereof to receive the elevated 35 portions of said sole. 35

2. In shoe making methods, that improvement 40 which includes incising a piece of sole material with cuts defining margins of an insole, said cuts extending to a depth corresponding to the thickness 45 of the insole desired, then rounding an outsole from said material in relation to the insole thus defined, depressing the sole over a central area of the ball portion thereof, splitting the sole above the depressed area and within the depth 50 of said cuts to provide a perforate insole and an outsole, lasting a shoe upper to the insole in secured relation, restoring the outsole to its normal undepressed condition and replacing it in its original relation to the insole and securing it 55 thereto and to the secured portions of the upper, and attaching a heel to the outsole. 60

3. In shoe making, the method of forming an 55 outsole and a complementary insole therefor by first forming a rounded sole with incisions cut 60 therein to define outer margins of an insole, said incisions extending to a depth corresponding to the thickness of the insole desired, and then splitting the sole within the depth of said incisions to obtain an insole therefrom. 65

4. In shoe making, the method of forming an 70 outsole and a complementary insole therefor from a single thickness of material consisting in first 75 incising the material with cuts defining outer margins of an insole, then rounding an outsole from said material in relation to the insole thus defined, and then splitting the material within the depth of said cuts. 80

5. In shoe making, the method of providing an 75 outsole and a complementary insole therefor which consists in first forming a rounded sole 80 with incisions cut therein to define margins of an insole, depressing the sole material over a central area of the ball portion thereof, then 85

5 splitting the sole above the depressed area and within the depth of said incisions to obtain a perforate insole therefrom, and then restoring the sole material to its normal undepressed condition.

10 6. In shoe making, the method of providing an outsole and a complementary insole therefor which consists in forming a full rounded sole with incisions cut therein to define margins of an insole, temporarily depressing the sole material over a central area of the ball portion thereof, then, while the sole is thus depressed, splitting the sole above the depressed area and within the depth of said incisions to obtain a

15 15 perforate insole therefrom.

20 7. A method of manufacturing an insole and outsole from a single piece of sole leather which includes providing a sole leather unit, forming a cut depthwise of said unit and in the face thereof opposite the grain side and parallel with and spaced inwardly from the edge line of the outsole when rounded, and thereafter splitting such unit to provide insole and outsole portions, with said cut defining the edge of the insole

25 portion.

8. A method of manufacturing an insole and outsole from a single piece of sole leather which includes providing a sole leather unit having the combined thickness of an insole and outsole, forming a cut depthwise of said unit toward the grain side for a depth substantially equal to said insole thickness and parallel with and spaced inwardly from the edge line of the outsole when rounded, and thereafter splitting such unit to

provide insole and outsole portions, with said cut defining the edge of the insole portion.

9. A method of forming insoles and outsoles which includes utilizing a sole leather unit having the combined thickness of an insole and outsole, forming in one face thereof a slit of a depth substantially equal to the insole thickness and defining the finished edge of the latter and thereafter splitting said sole unit along the bottom of said slit to provide insole and outsole 10 portions and to detach from said unit those portions of the inner sole located outwardly from said slit.

10. A method of manufacturing an insole and outsole from a single piece of sole leather which 15 includes providing a sole leather unit, forming a cut depthwise of said unit and in the face thereof opposite the grain side and parallel with and spaced inwardly from the edge line of the outsole when rounded, rounding said unit to the shape of 20 the outsole, and splitting such unit to provide insole and outsole portions, with said cut defining the edge of the insole portion.

11. An apparatus of the character described including in combination an outsole pattern, a 25 trimming means cooperating therewith adapted to be actuated to round an outsole from a sole leather blank, a clamp for retaining said blank in association with such pattern, and cutting means forming a part of said apparatus and acting upon movement of said clamp to hold the sole blank with respect to said pattern to form a cut in such blank defining an insole edge.

FRED MACCARONE.
